UNITED STATES PATENT OFFICE

WALTER P. MURPHY, OF CHICAGO, ILLINOIS, ASSIGNOR TO UNION METAL PRODUCTS COMPANY, OF CHICAGO, ILLINOIS, A CORPORATION OF DELAWARE

WALL FOR RAILWAY CARS

Application filed April 19, 1930. Serial No. 445,658.

My invention relates to walls for railway house cars comprising a metallic exterior sheathing and interior wooden lining with metallic posts therebetween and the object of the invention is to reinforce the wooden lining against the shifting lading by forming offset panels in the metallic sheathing between adjacent posts, which panels bear against and back up the wooden lining so as to reinforce it against deflection.

While efforts are made to block the lading in the car the shocks caused by the heavy locomotive, emergency air brake and the classification hump, tear the lading away from its moorings and throw it against the end wall of the car and the lateral weaving of the car throws it against the side wall of the car.

Another object is to provide nailing strips for the wooden lining which are secured to the posts and formed so as to space the wooden lining away from the posts to provide a smooth nailing surface even though the nailing strip should shrink. It is preferable to have the lining bear against the nailing strip rather than against the metallic post.

Another object is to form an offset panel in the metallic sheathing to reinforce and strengthen the wall and at the same time provide a bearing surface for the lining boards.

In the drawings:

Fig. 1 shows an end of a railway box car having one form of my improved device applied thereon.

Fig. 2 is a section on line 2—2 of Fig. 1.

Fig. 3 is a section on line 3—3 of Fig. 1.

Fig. 4 shows an end wall of a railway car comprising a modified construction of my device.

Fig. 5 is a section on line 5—5 of Fig. 4.

Fig. 6 is an enlarged section on line 6—6 of Fig. 1.

Fig. 7 shows a modified post arrangement.

The usual railway box car is provided with an end sill 1; end plate 2 and corner posts 3

which constitutes a rectangular frame for the end wall.

In the form illustrated in Figs. 1, 2, 3 and 6 the end wall comprises a plurality of metallic plates 5—6 secured together along a horizontal line 7 forming a metallic sheathing which is secured to the end plate 2, end sill 1 and corner posts 3 in any convenient manner. The end posts 9 extend vertically and are secured to the sill and plate respectively. 55 The wooden lining 10 comprises a plurality of horizontal boards which are secured to the end posts 9 and also preferably to the corner posts of the car. In order to prevent the shifting lading from breaking the lining between the several end posts or between an end post and the corner post, I form the metallic sheathing with offset panels 12 between adjacent posts which engage the lining so as to reinforce it against deflection. 60

The lining boards may be bolted to the end posts but I prefer to form each end post with a recess 13 into which a nailing strip 15 is seated. This nailing strip is secured to the end posts preferably by the bolts 16 and is extended so as to space the lining apart from the posts. The nailing strip 15 and offset panels 12 of the sheathing are flush with each other so that they both support the lining. 65

In the form illustrated in Figs. 1 and 2 the offset panels extend to adjacent the seam 17 between the upper (5) and lower (6) plates forming the metallic sheathing, whereas Fig. 4 shows a modified construction wherein the 80 plates are secured together along vertical lines 20 and the offset panels 21 extend from adjacent the end plate 2 to adjacent the end sill 1 of the car. The seam 17 forms a belt rail or girth which strengthens the end (or side) wall 85 at a vital point (about a third of the distance between the sill 1 and plate 2) and also strengthens the embossed panels 5 and 6 by reducing their length.

I preferably space the end posts 9 so as to 90

divide the horizontal width of the end wall into substantially equal spaces, as shown in Figs. 4 and 5, so that the offset panels 21 may be made from the same dies.

5. Fig. 7 shows a modified construction wherein the end posts 24 have a central channel or recess into which the nailing strip 25 is fitted and secured thereto by bolts 26.

The accompanying drawings illustrate the 10 preferred form of the invention, though it is to be understood that the invention is not limited to the exact details of construction shown and described, as it is obvious that various 15 modifications thereof, within the scope of the claims, will occur to persons skilled in the art.

I claim:

1. In a railway car, the combination of a plurality of posts, a metallic sheathing comprising a plurality of plates secured together along horizontal lines overlapping the outside of the posts and secured to the posts, a nailing strip attached to each of the posts and horizontal boards forming a wooden lining secured to the nailing strips, each of said plates formed with an offset panel between adjacent posts engaging the lining so as to reinforce it against deflection.

2. In a railway car having a horizontal sill and a horizontal plate, the combination of a plurality of vertical posts with their opposite ends secured respectively to the sill and plate, a metallic sheathing consisting of a plurality of plates secured together on a horizontal line positioned on the outside of said posts and secured thereto, each of said plates formed with an offset panel with their sides terminating adjacent said posts, the panels in the upper plates terminating adjacent said plate and line, respectively, and the panels in the lower plates terminating adjacent said sill and line, respectively, so as to form a girth at said horizontal line.

3. In a railway car having a horizontal sill and a horizontal plate, the combination of a plurality of vertical posts with their opposite ends secured respectively to the sill and plate, a metallic sheathing consisting of a plurality of plates secured together on a horizontal line positioned on the outside of said posts and secured thereto, each of said plates formed with an offset panel with their sides terminating adjacent said posts, the panels in the upper plates terminating adjacent said plate and line, respectively, and the panels in the lower plates terminating adjacent said sill and line, respectively, so as to form a girth at said horizontal line, a wooden lining engaging the panels to reinforce them against deflection, and means to retain said lining in place.

4. In a railway car having a horizontal sill and a horizontal plate, the combination of a plurality of vertical posts with their opposite ends secured respectively to the sill

and plate, a metallic sheathing consisting of a plurality of plates secured together on a horizontal line positioned on the outside of said post and secured thereto, each of said plates formed with an offset panel with their sides terminating adjacent said posts, the panels in the upper plates terminating adjacent said plate and line, respectively, and the panels in the lower plates terminating adjacent said sill and line, respectively, so as to form a girth at said horizontal line, the panels in the upper plates being longer than the panels in the lower plates.
